UNITED STATES PATENT OFFICE.

JOHN P. POLNASZEK, OF MINNEAPOLIS, MINNESOTA, ASSIGNOR OF ONE-HALF TO
ANDRE L. PINET, OF ROBBINSDALE, MINNESOTA.

GRAIN-CAR STRUCTURE.

Application filed April 19, 1926. Serial No. 102,844.

This invention relates to box car construction and especially to an attachment for facilitating the removal of grain doors employed in standard box cars.

5 It is the main object of this invention to provide an extremely simple but highly efficient box car construction or attachment therefor, which will quickly deliver the grain within a car adjacent the grain doors 10 at either side of the car, thereby permitting the grain doors to be readily removed without becoming damaged.

A further object of the invention is to provide an attachment for a freight car 15 adapted to carry grain which may be readily manipulated from without the car to unload that portion of the carried grain exerting pressure against the grain doors.

More specifically it is an object to provide 20 in combination with a freight car provided with the usual side door ways, passages through the bottom thereof adjacent the doors and slideable gates for closing or opening said passages adapted to be operated 25 from without the car and normally held in closed position.

A still further object is to provide in combination with this device, a delivery chute 30 for each passage, adapted to drop the grain at the respective sides of the car in the usual grain pits.

These and other objects of the invention 35 will be apparent in the following description made in connection with the accompanying drawings, in which like characters refer to similar parts throughout the several views, and in which

Fig. 1 is a fragmentary side elevation of 40 a portion of a box car made in conformance with my invention.

Fig. 2 is a cross section on the line 2—2 of Fig. 1.

Fig. 3 is a vertical section taken on the line 3—3 of Fig. 2.

45 Fig. 4 is a detail cross section of one of my devices on a larger scale taken on the line 4—4 of Fig. 1 and showing my device sealed up for shipment, and

50 Fig. 5 is a fragmentary cross section of my device showing the connection of the operating handle with the gate.

A preferred embodiment of my invention 55 is shown in combination with a standard freight car of the box type. The car comprises the sides 6 having the usual door ways

formed in the central portions thereof, and supported on the longitudinally extending central beams 7 and the side beams 8. The bottom of the car is indicated by the numeral 9 and a grain door of any suitable construction is indicated by the numeral 10 mounted within one of the door ways.

55 I preferably recess the sides of the car bottom 9 centrally of the door ways to afford a pair of rectangular passages immediately adjacent the grain doors 10 when the latter are employed. On the sides of each of these

70 passages guide means are formed, preferably by securing angular bars 11 to the edges of car bottom 9 about said passages.

Angular bars 11 carry inwardly projecting tongue portions 11^a forming rectangular flanges in the inner sides of each of the

75 passages. A gate designated as an entirety A normally closes each of the passages de- 75

scribed and comprises an upper rectangular plate 12 and a lower rectangular plate 13 riveted or otherwise secured to plate 12 and provided at its edges with downwardly and

80 outwardly curved flanges 13^a, the edges of plate 12 and flanges 13^a are spaced apart to

85 snugly engage the tongues 11^a on angle bars 11, whereby slideable engagement is made between gates A and guides 11. Angle bars 11 may be inset slightly on the car bottom 9

85 whereby the top plate 12 of gates A may be maintained flush with the upper surface of bottom 9. Inasmuch as the passages are formed by recessing the side edges of the

90 floor 9, it will be seen that my gates may be withdrawn outwardly of the car.

95 Secured to the bottom plate 13 of each of the gates is an inwardly extending arm or link 14 preferably carrying at its inner end an eye 15, to which is secured one end of a coiled spring or other elastic member 16.

Spring 16 may be secured at its other end to one of the central beams 7 thereby resili- 95

ently holding the gate in closed position.

An operating handle 17 is secured by 100 means of a chain or other flexible member 18 to the front end of each of the gates, fa-

105 cilitating the opening thereof from without the car. Beneath and on the inner side of each of the passages described I provide a

110 hood or delivery chute 19 of preferably segmental form, adapted to direct the grain downwardly and outwardly and dropping the same at the sides of the car. The grain

115 is usually delivered to the grain pits, which

are located close to the rails on which the cars are supported, whereby my device will deliver the grain without waste. An aperture is provided in the rear of each of hoods 19 through which the arms 14 may work.

To seal my device when the car is filled and dispatched I provide a strap 20 secured to the bottom plate 13 of the door and adapted to be slipped over a staple 21 mounted on the outer beams 8 through which the seal 22 may be inserted if desired.

The operation of the above described device is probably obvious from the foregoing description, but may be briefly summarized as follows:

When it is desired to unload the grain car, the handle 17 may be pulled, thereby permitting the grain in the central portion of the car adjacent the grain door to be withdrawn. Two or three minutes is sufficient time to remove a substantial portion of the grain pressing against the grain door. The grain door may be then readily removed without destroying the same as is the usual custom. After the grain doors are removed the automatic shovels may be employed and the car unloaded in the usual manner.

The time factor in destroying the grain door is an important one, as well as the waste and expense of providing new grain doors for every shipment. My device permits the car to be rapidly unloaded without impairing in any way the grain doors employed.

As has been stated, the grain delivered through the hoods 19 is dropped at the side of the car and into the usual grain pits.

It will be noted that my gates A employed, overlap the tongues 11^a sufficiently to form leak proof closures for the passages and are moreover resiliently held in closed position by the springs 16.

From the above description it will be seen that I have invented a highly efficient improvement in box car construction, which may be readily applied as an attachment for standard box cars now in use, and which will accomplish results heretofore unattained.

It will, of course, be understood that various changes may be made in the form, details, arrangement and proportions of the parts, without departing from the scope of applicant's invention which, generally stated, consists in a device capable of carry-

ing out the objects above set forth, in the novel parts and combinations of parts disclosed and defined in the appended claims.

What is claimed is:

1. In a freight car having the usual doorway adapted to receive a grain door, said car having a floor opening immediately adjacent said doorway, a delivery chute extending downwardly and outwardly from said floor opening, a gate horizontally movable across said opening and outwardly from the doorway of said car, means for normally holding said gate inwardly in closed position, and means for opening said gate from without said car, whereby material in the car pressing against the grain door may be withdrawn to permit the grain door to be removed.

2. In a freight car having the usual doorway adapted to receive a grain door, said car also having a floor opening immediately adjacent said doorway, a delivery chute extending downwardly from said floor opening, said chute having an aperture in the rear side thereof, a gate horizontally movable across said opening outwardly of said doorway, a gate rod extending through the aperture in said chute and connected to said door, elastic means connected to said gate rod and said car for normally holding said gate closed, and a handle on the outer end of said gate adapted to be manipulated from without said car, whereby congestion against the grain door may be removed.

3. In a freight car having the usual doorway adapted to receive a grain door, said car also having a substantially rectangular floor opening immediately adjacent said doorway, a delivery chute extending downwardly from said floor opening, said floor opening having a substantially rectangular flange or shoulder about the periphery thereof, a gate horizontally slidable across said opening substantially flush with said floor, the edges of said gate being adapted to overlap said flange or shoulder of said door opening, means interposed between said gate and said car for yieldingly holding said gate in closed position, and means extending without said car for opening said gate whereby congestion against the grain door will be removed.

In testimony whereof I affix my signature.

JOHN P. POLNASZEK.
